UNITED STATES PATENT OFFICE.

GWYNETH DUNSTER BAKER, OF BROOKLINE, MASSACHUSETTS.

TABLE.

1,369,214.

Specification of Letters Patent

Patented Feb. 22, 1921.

Application filed August 16, 1920. Serial No. 403,740.

To all whom it may concern:

Be it known that I, GWYNETH DUNSTER BAKER, a citizen of the United States, residing at Brookline, in the county of Norfolk and State of Massachusetts, have invented 5 certain new and useful Improvements in Tables, of which the following is a specification.

My invention relates to improvements in 10 tables, and particularly to means whereby electrical connections for heating devices may be invisibly introduced from the under side of the table to the upper surface and when not in use may be dropped beneath 15 the table, but in position to be immediately reached when wanted.

My invention also relates to an attachment 20 for tables, which can be easily and cheaply applied to existing tables, for holding the necessary wires and connecting members beneath the table, but in such a manner that the connection can be made to an electrical heating unit upon the upper 25 surface of the table, instantly, and the heating unit may be instantly disconnected, so that when disconnected, no sign of the electrical connection will be visible.

In the drawings, Figure 1 is a cross-section 30 of a table, showing my improvement applied thereto. Fig. 2 is a plan view, on an enlarged scale, of the upper part of the device; Fig. 3 is a cross-section on the line 3—3 of Fig. 2; Fig. 4 is a horizontal section on the line 4—4 of Fig. 3.

The object of the invention is to provide 35 tables and the like with a simple, unobtrusive and efficient means to connect objects upon the table, such as electric lamps and heater units, with a source of electrical energy and to this end an aperture is formed 40 in the table, usually at the center, and in this aperture is mounted my device, which may be of wood or metal, and may be colored to match the table of which it is to 45 form a part.

In Fig. 1, I have shown a table A of ordinary design in which is mounted one of my devices, which is shown in detail and on an enlarged scale in Figs. 2, 3 and 4. In the 50 preferred form shown in the drawings, the main frame or support 1 is cruciform, the arms being slightly longer than the diameter of the aperture in the table, into which the device is fitted, four recesses being 55 formed about the edge of the aperture into

which the ends 1^a of the arm are received, so that the upper surface of the cruciform top of the device is flush with the upper surface of the table. Below the member 1 is a basket, made up of arms 2 connected 60 at their lower ends by a split ring 3 one section 3' of which is hinged or so shaped that it will open to permit passage of the wire 4^a and the plug 4 of the electric connection, the aperture of the ring 3 being 65 designedly too small in diameter to pass the plug 4.

Between the arms of the cruciform member 1 are fitted flaps 1^b which are hinged to the adjacent arc of member 1, so that they 70 can move in either direction, a centering spring 1^c being mounted upon the hinge pintle which holds the flaps 1^b normally in a horizontal position flush with the surface of the table A. Between the abutting edges 75 of flaps 1^b a space 1^d is formed, of size sufficient to receive the ordinary wire of an electrical connection.

The operation is as follows: The device 80 having been fitted to the table with which it is to be used, the plugs and wire of the electrical connections are introduced into the basket through the section 3' of ring 3. More than one wire and plug may obviously 85 be so introduced, if more than one electrical connection is desired. When it is desired to make an electrical connection, the hand of the operator is passed into the basket from above, between flaps 1^b of member 1, and a plug 4 is drawn upward and connected with 90 the desired object, such as a lamp or heater, the flaps 1^b closing below the plug and the wire 4^a resting in space 1^d between the abutting edges of the flaps 1^b. When the use is 95 no longer desired, the plug is disconnected and dropped, and will immediately disappear through the flaps, into the basket below. The cross pieces of the member 1 are sufficient to support any object which 100 may be placed thereon, as well as to support the basket below. The upper member 1 may be permanently or detachably connected with the arms 2 of the basket, and I do not intend to limit myself to the precise form of construction shown and described.

As will be obvious, the member 1 may be removed from the table when not in use, and the aperture closed by a wooden cover to match the wood of the table. For this purpose the piece which has been cut out 110

of the table may be preserved and when replaced the cut will hardly be discernible.

I claim:

1. A table, provided with an aperture in its plane surface; a plate designed to fit and fill said aperture and having notches at or near its peripheral edges to pass and retain the plug and wire of an electrical connection; a receptacle secured beneath the aperture to receive and retain the electrical plugs when dropped through the plate, all organized substantially as and for the purpose described.

2. A table, provided with an aperture in its plane surface; a removable plate designed to fit and fill said aperture and made up of a cruciform member, each arm of which carries a flap hinged thereto, to swing in either direction; and normally supported in and returned to a horizontal plane by a spring, the flap having a notch in its edge to pass

the wire of an electrical connection; a receptacle secured beneath the aperture, to receive and retain the electrical plugs when dropped through the plate, all organized 25 substantially as and for the purpose described.

3. A table, provided with an aperture in its plane surface; a plate designed to fit and fill said aperture and having notches at or 30 near its peripheral edges to pass and retain the plug and wire of an electrical connection; a receptacle secured beneath the aperture, made up of a split ring and a set of inwardly curved arms, connected at their 35 upper ends to the table and at their lower ends to the split ring, all organized substantially as and for the purpose described.

Signed at Boston, Massachusetts, this sixth day of August, 1920.

GWYNETH DUNSTER BAKER.
